HARNESS FOR CROSS-WEAVING

George Hilton, Northbridge, Mass., assignor to
Steel Heddle Manufacturing Company, Phila-
delphia, Pa., a corporation of Pennsylvania

Application July 8, 1944, Serial No. 544,026

6 Claims. (Cl. 139—50)

This invention relates to harness for cross-weaving, and it is particularly adaptable for use in connection with the modern flat steel doup needles and lifting heddles now commonly used for cross-weaving. This invention serves to eliminate the jumper harness and the mechanism for operating the same customarily used in connection with such devices, and it also takes the place of the easer bar, and the springs or other devices used in connection therewith, for maintaining the requisite tension on the doup threads.

At the present time most of the leno or cross-weaving is done by means of flat steel harness of the type shown in the Kaufmann Patents No. 1,037,150 and No. 1,037,151, in which there is provided, for pairs of warp ends, a flat steel doup needle or half heddle having an eye in the end thereof for controlling the doup thread, and two standard or lifting heddles between which the ground thread extends and which alternatively raise the doup thread on one side or the other of the ground thread, thereby to bring about the requisite twist of the warp ends during the weaving operation.

However, in the use of harness of the type aforesaid, as well as in connection with certain other types of doup harness, it has been considered necessary to employ a jumper harness including individual heddles through which the ground ends are entered, and an easer bar, usually spring controlled, for maintaining the desired tension on the doup ends yet permitting the same to be raised and lowered as required. Mechanism for operating the jumper harness in timed relationship has also been required so that the ground ends are also raised and lowered at the proper times and to the proper extent.

The principal object of the present invention is to provide a simple and inexpensive yet efficient device, which will be automatic in its action, which will eliminate the necessity of employing the jumper harness and its actuating mechanism, and which will also take the place of the easer bar heretofore used for maintaining the tension of the doup ends.

The nature and characteristic features of the invention will be more readily understood from the following description taken in connection with the accompanying drawings forming part hereof, in which:

Figure 1 is a diagrammatic view illustrating a typical arrangement of doup harness and having the device of the present invention associated therewith, the doup and ground ends, respectively, being shown in neutral positions;

Fig. 2 is a similar view in which, however, the doup needle, and the warp thread controlled thereby, is shown as having been raised by one of the standard or lifting heddles;

Fig. 3 is a fragmentary elevational view of a portion of a loom with a device embodying the main features of the present invention shown in connection therewith;

Fig. 4 is a top or plan view of the apparatus shown in Fig. 3; and

Fig. 5 is a section taken on the line 5—5 of Fig. 3.

Referring now more particularly to Figs. 1 and 2 of the drawings, in the arrangement there shown, 10 is the beam from which the warp ends are fed as the same are woven into the fabric. The sheet of warp extends over the whip roll 11, thence being separated by the lease rods 12 and 13. If desired, a stop motion may be used as indicated at 14. The warp ends then extend to the harness, some or all of said warp ends being separated into pairs of doup threads 15 and ground threads 16. Each doup end 15 extends through the eye 17 of a doup needle 18 which preferably is of the type shown in the Kaufmann Patent No. 1,037,151, hereinbefore referred to. The doup needle 18 is controlled in the usual manner by the standard or lifting heddles 19 and 20 and the ground end 16 of a particular pair passes between the lifting heddles 19 and 20 in the usual manner.

The device comprising the principal part of the present invention is preferably interposed between the stop motion and the weaving harness, usually being positioned immediately above and in front of the crank shaft 21 of the loom. Said device consists essentially of a pair of rods 22 and 23 extending across the loom, said rods being mounted in rocker arms 24 at their respective ends. Each of the rocker arms 24 is provided with a trunnion 25 which is pivotally mounted in a bearing block 26.

The bearing block 26, on each side, is slidably mounted in a slot 27 in a supporting bracket 28 and normally is impelled downwardly by means of a coil spring 29. The lower end of the coil spring 29 bears against the bearing block 26 and the upper end of said spring is engaged by the lower end of an adjusting screw 30 which is threaded in the upper portion of the bracket 28.

The bracket 28 is fixedly secured to another bracket 31 by means of bolts 32, and said bracket 31 is adjustably secured by means of a bolt 33 to the slotted vertical leg portion of an angular bracket member 34. The horizontal portion of the angular bracket member 34 is adjustably se-

cured by a bolt 35 to a horizontal portion of another angular bracket 36, a vertical portion of which is fixedly secured by a bolt 37 to the side frame 38 of the loom.

The foregoing arrangement of brackets is provided so that the device may be readily mounted in various types of looms, it being, of course, understood that the warp ends must be kept clear of the crank shaft 21 at all times.

In entering the warp in the loom the doup threads 15 are passed over the rearmost rod 22 and under the foremost rod 23, whereas the ground threads 16 are passed under the rearmost rod 22 and over the foremost rod 23. The operation of the device of the invention may now be explained.

Referring now more particularly to Fig. 1 of the drawings, it will be noted that when the parts of the weaving harness are in neutral positions, as shown in Fig. 1, the transverse rods 22 and 23 of the device of the present invention will occupy certain positions resulting from the relative tension of the doup threads 15 and the ground threads 16. When, however, the warp is shedded, for the purpose of passing the shuttle, one or the other of the lifting heddles will be raised to cause the doup thread 15 of each pair to pass on one side or the other of the ground thread 16 of said pair, according to which of the lifting heddles is raised, all of which will be readily understood by those familiar with this art.

When the doup threads 15 are raised, on either side of their respective ground threads 16, this causes a greater tension to be imparted to the doup threads 15 and would ordinarily slacken the ground threads 16. However, with the device of the present invention, when the doup threads 15 are raised the foremost bar 23 will thereby be raised and, by reason of the pivotal mounting of the rocker arms 24, the rearmost rod 22 will be simultaneously lowered but to a much greater extent, and thereby automatically serve to take up the slack of the ground ends 16 and insure the proper formation of the weave.

It will, of course, be noted that the bearing blocks 26, in which the trunnions 25 of the rocker arms 24 are pivoted, are permitted a limited amount of vertical movement under the regulatable tension imparted by the coil spring 29 and the adjusting screw 30. This arrangement permits the rocker arms, and the transverse rods 22 and 23 carried thereby, to be unitarily raised to a limited extent and thereby prevents undue tension being imparted to the warp at certain times in the operation of the harness.

I claim:

1. In harness for cross-weaving, in combination with means for raising the doup threads alternatively on one side or the other of their respective ground threads, of means actuated by the tension of the doup threads for automatically taking up the slack of the ground threads when the doup threads are raised.

2. In harness for cross-weaving, the combination with means for raising the doup threads alternatively on one side or the other of their respective ground threads, of means controlled by the tension of the doup threads for automatically taking up the slack of the ground threads, and resilient means for relieving the tension of the warp when required.

3. In harness for cross-weaving, in combination with means for raising the doup threads alternatively on one side or the other of their respective ground threads, of a pair of transverse rods extending across the loom, the doup threads passing under one of said rods and the ground threads passing under the other of said rods, and a positive connection between said rods whereby when one of said rods is raised by the tension of said doup threads the other of said rods will be automatically depressed and thereby take up the slack of the ground threads.

4. In harness for cross-weaving, in combination with means for raising the doup threads alternatively on one side or the other of their respective ground threads; of a pair of transverse rods extending across the loom, the doup threads passing under one of said rods and the ground threads passing under the other of said rods, and freely pivoted rocker arms supporting said rods whereby when one of said rods is raised by the tension of said doup threads the other of said rods will be depressed and thereby take up the slack of the ground threads.

5. In harness for cross-weaving, in combination with means for raising the doup threads alternatively on one side or the other of their respective ground threads, of a pair of transverse rods extending across the loom, the doup threads passing under one of said rods and the ground threads passing under the other of said rods, rocker arms supporting said rods whereby when one of said rods is raised by the tension of said doup threads the other of said rods will be depressed and thereby take up the slack of the ground threads, and a spring mounting for said rocker arms permitting a limited unitary elevation of said rocker arms and the transverse rods carried thereby.

6. In harness for cross-weaving, in combination with means for raising the doup threads alternatively on one side or the other of their respective ground threads, of a pair of transverse rods extending across the loom, the doup threads passing under one of said rods and the ground threads passing under the other of said rods, means for supporting said rods whereby when one of said rods is raised by the tension of said doup threads the other of said rods will be depressed and thereby take up the slack of the ground threads, and a spring mounting for said supporting means permitting a limited unitary elevation of said transverse rods to relieve the tension on the warp when required.

GEORGE HILTON.
